MUSICAL WATER TOY

Clair O. Musser, 12997 Blairwood Drive,
Studio City, Calif. 91604

Filed Feb. 16, 1966, Ser. No. 1,096

Term of patent 7 years

(Cl. D34—15)

FIG. 1.

FIG. 2.

FIG. 3.

FIG. 4.

FIG. 5.

FIG. 6.

FIG. 7.

FIG. 8.

FIGURE 1 is an isometric view of a musical water toy showing my new design thereof;

FIGURE 2 is a front elevational view thereof, the rear elevational view being identical;

FIGURE 3 is a left end elevational view thereof, the right end elevational view being identical;

FIGURE 4 is a bottom plan view thereof;

FIGURE 5 is an isometric view of the musical water toy wherein a handleline has been attached about the periphery of the ring;

FIGURE 6 is a front elevational view thereof, the rear elevational view thereof being identical;

FIGURE 7 is a left end elevational view thereof, the right end elevational view thereof being identical; and

FIGURE 8 is a bottom plan view thereof.

I claim:

The ornamental design for a musical water toy, substantially as shown and described.
